COMBINED MULTIPLE SOCKET WRENCH AND SPANNER

William James Stitt, Jr., 1320 Lynette Way,
Sacramento, Calif. 95831

Filed Aug. 2, 1972, Ser. No. 277,350

Term of patent 14 years

Int. Cl. D8—05

U.S. Cl. D8—26

FIG. 1 is a top front perspective view of a combined multiple socket wrench and spanner, showing my new design;

FIG. 2 is a bottom rear perspective view;

FIG. 3 is a top plan view, the bottom plan being in mirror symmetry;

FIG. 4 is a front end view;

FIG. 5 is a rear end view; and,

FIG. 6 is a sectional view, the plane of the section being indicated by the line 6—6 in FIG. 3.

I claim:

The ornamental design for a combined multiple socket wrench and spanner, as shown and described.
